CABINET FOR A FILM PROCESSING MACHINE

Conrad E. Lee, Minneapolis, Minn., assignor to
Pako Corporation, Minneapolis, Minn.

Filed Aug. 22, 1969, Ser. No. 18,827

Term of patent 14 years

Int. Cl. D16—06

U.S. Cl. D61—1

FIG. 1

FIG. 2

FIG. 3

FIG. 4

FIG. 5

FIG. 1 is a perspective view of a cabinet for a film processing machine showing my new design.

FIG. 2 is a top plan view thereof.

FIG. 3 is a side elevational view.

FIG. 4 is a rear view.

FIG. 5 is a front elevational view thereof.

I claim:

The ornamental design for a cabinet for a film processing machine, as shown.
